HERMETICALLY SEALED ELECTROMAGNETIC RELAY

Jack S. Hawkins, San Jose, Calif., assignor to Jennings
Radio Manufacturing Corporation, San Jose, Calif., a
corporation of Delaware

Filed Sept. 17, 1963, Ser. No. 76,617

Term of patent 14 years

(Cl. D26—13)

FIG. 1 is a perspective view of a hermetically sealed electromagnetic relay showing my new design;

FIG. 2 is an end elevational view of the relay as seen from the top of FIG. 1;

FIG. 3 is an end elevational view as seen from the bottom of FIG. 1;

FIG. 4 is a perspective view of the relay on a somewhat reduced scale.

I claim:

The ornamental design for a hermetically sealed electromagnetic relay, as shown.
